TREAT T. PROSSER, OF CHICAGO, ILLINOIS, ASSIGNOR TO HIMSELF,
GEORGE W. GILLETT, AND GEORGE H. ROZET.

Letters Patent No. 86,034, dated January 19, 1869.

IMPROVEMENT IN SASH-BALANCE.

The Schedule referred to in these Letters Patent and making part of the same.

To all whom it may concern:

Be it known that I, TREAT T. PROSSER, of Chicago, in the county of Cook, and State of Illinois, have invented certain new and useful Improvements in the Method of Constructing and Operating Sash-Weights; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to hanging sash, and consists in connecting the sash to weights, of peculiar form and construction, by bands or straps passing over flat pulleys or rollers.

In the drawings—

Figure 1 is a perspective view, with a portion of the casing broken away, to show the arrangement of the weight;

Figure 2 is a transverse section of the casing or frame through the centre of the pulleys, showing the strap, passing over one of them, with the weight attached, and the other with the strap in section, and in red, but without the weight; and

Figure 3 is a longitudinal vertical section of the weight, with strap attached.

In the old method, it is customary to attach a cord to each edge of each sash, at or near the top of the sash, and then to pass its loose end over a sheave-pulley, set in the jamb of the casings of the window-frame, and then down into the weight-chamber, and there connect it, by tying, to a weight of cylindrical form, and provided with an eye or hook for that purpose.

When the sash and weight about balance each other, it is evident that very little force will be required to move the sash, and it would therefore seem of little importance what kind of weights and connections were used, provided the former balanced the sash, and the latter were strong enough for the purpose; but experience brings to light the fact that, in nearly every house provided with balanced sash, more or less of these sash are inoperative, because of certain derangements caused by the weights, in untwisting the cord, &c.

The weight, being cylindrical in form, when attached to and suspended by the cord, commences to turn, and thus untwist the cord, destroying at once much of its usefulness and durability; and besides, as the cord rests on the sheave-pulley, the weight of the sash and sash-weight prevents it from passing freely over the pulley, and, as the sash is shoved up, the twist is forced into it on the side toward the sash, and it frequently kinks, thus preventing its free passage over the pulley, and oftentimes tearing or breaking it loose from the sash.

The weights ordinarily used are solid, as well as cy-

lindrical in form, and, from the great number of them used, have become an extensive and important article of trade.

To obviate the difficulties above described, and at the same time to make and use devices of simpler construction, and cheaper in cost, is the object of my invention.

In doing this, I attach, near the upper ends of the edges of the sash, B, bands or straps e, at one end, and pass the other end up over flat pulleys c, turning on pins f, and then down into the weight-chambers g, behind the casings D, and there connect it to a weight, H, by passing a small screw or rivet, o, through the slotted end of the weight, and an eyelet in the end of the strap, all as clearly shown in figs. 1 and 2.

The weight H, I make of an oblong rectangular form, by casting iron about a core of sand. This I do by anchoring or suspending the core J in the centre of the mould, by supports m, and inserting in the end of the core J a small roll of thin metal, n, and pouring the liquid metal about it.

The supports m hold the core J in position, while the small roll of thin metal, n, furnishes an open passage for the gases, that are generated in the casting, to escape.

The form of the weight H, with its slotted end for attaching the strap e, and with its core J, of sand, is clearly shown in fig. 3.

As the weight is thus constructed, there is a saving of metal equal to the weight of the sand, and, when the quantity of weights used is large, it is obvious that there must be a great saving of metal. As they are rectangular in form, they cannot turn in the weight-chambers if of corresponding form, and will not, when attached to flat braids, bands, or straps e, passing over flat pulleys c. As the weights cannot turn, the straps cannot twist, and consequently there can be no jamming, but, on the other hand, everything must run easily and smoothly.

Window-sash can not only be hung cheaper by these devices, arranged as described, but, when once so hung, will continue to operate readily and easily till worn out.

Having thus described my invention,

What I claim, is—

1. A hanging for sash consisting of a flat strap, e, passing over a smooth roller, c, with the weight H attached, constructed and arranged to operate substantially as herein described.

2. The method of constructing the weight H, with a core of sand, and of attaching it to the strap e, substantially as herein described and for the purpose set forth.

TREAT T. PROSSER.
